Des. 135

W. J. Woolson, Cleveland, Ohio.

Letter Patent Design No. 135. dated 14th July 1847.

The schedule referred to in these Letters Patent and marking part of the same

To all whom it may concern: Be it known that J. C. Woolson of Cleveland in the County of Cuyahoga and State of Ohio, has invented and produced a new and useful Design for the front plate of a stove of the kind usually denominated the Franklin Stove; and I do hereby declare that the following is a full and exact description thereof, reference being had to the accompanying drawings on which my ornamental design is clearly represented.

The shape and configuration of the plate is designated by the general outline of the drawing; the ornament on its upper portion, or breast, consists of the scroll work leafing A, A' and B. Its sides, or jambs have on them the ornamental leafing shown at C, C, and one of them has on its lower end the antique male head D; and the other the antique female head E. There are following doors F, and G, the door F, having on it the figure H, representing a man in the act of smoking a pipe, and with a tamper in his hand; and the door G, a female figure I, in the act of taking snuff; each of these doors are surrounded by an ornamental border J, and they are usually hinged to the jambs by hinges in the form of a hand, and fore arm K.

Having thus distinctly represented and described the nature and arrangement of the respective ornaments and figures upon the front plate of my Franklin Stove, what I claim therein as new and desire to secure by Letter Patent, is the configuration and arrangement of said ornaments, as herein designated and represented.
